UNITED STATES PATENT OFFICE

WILLIAM M. SHEEHAN, OF ST. LOUIS, MISSOURI, AND WILLIAM S. MCGILVRAY, OF GRANITE CITY, ILLINOIS, ASSIGNEES TO GENERAL STEEL CASTINGS CORPORATION, OF GRANITE CITY, ILLINOIS, A CORPORATION OF DELAWARE

CAR TRUCK

Application filed May 23, 1930, Serial No. 455,017, and in Italy April 15, 1930.

The invention relates to railway rolling stock and consists in a novel spring plank and spring plank suspending structure for railway car trucks of the type in which the bolster is mounted upon springs carried by a spring plank extending across the truck from side to side and hung from the truck frame by swinging links.

One of the objects of the invention is to increase the clearance between the rail and the spring plank and associated parts and this object is accomplished by shortening the suspension links and pivoting the lower ends directly to the spring plank thereby eliminating the cross bar extending below the spring plank and carried by the links, which arrangement has been in general use heretofore.

Another object of the invention is to provide for vertical adjustment of the bolster. This object is accomplished by making the spring plank reversible, top for bottom, and locating the spring mounting surfaces of the opposite sides of the spring plank at different distances from the pivotal connection to the swinging links.

These and other detailed objects of the invention are attained by the structure illustrated in the accompanying drawings in which—

Figure 1 is a top view of one-half of a four wheel truck of the type referred to and equipped with the invention.

Figure 2 is, in part, a side elevation of the structure shown in Figure 1 and, in part, a longitudinal vertical section through the bolster, truck frame and spring plank and link.

Figure 3 is a vertical transverse section taken on the line 3—3 of Figure 1.

Figures 4, 5 and 6 illustrate a modified form of the invention in which Figure 4 is, in part, a top view of a different form of spring plank and, in part, is a section on the line 4—4 of Figure 5; Figure 5 is, in part, an end view of the spring plank, and, in part, a vertical sec-

tion on the line 5—5 of Figure 4; Figure 6 is a side elevation of the spring plank.

The truck illustrated in Figures 1, 2 and 3 includes wheels 1, journal boxes 2, equalizers 3, which are carried on the journal boxes and which mount coil springs 4 supporting the truck frame 5. This truck frame is here shown as a single casting, the sides of which are connected by end transoms 6 and center transoms 7. Swinging links 8 are suspended from the end portions of transoms 7 by means of pins 9. To this point the structure described corresponds to structures previously in use.

The spring plank 10, which is carried by the links 8, is of shallow box-like section from end to end and at its ends is provided with lateral extensions 11 each having a rectangular vertical opening 12 through which the lower end of a corresponding link 8 may project. A suitable pin 13 extends horizontally through the portions of each extension 11 which form the sides of the opening 12 and through the lower end of the link positioned in the opening. Preferably, the spring plank and the link will be provided with bushings 14 and 15, respectively, seating pin 13, and a cotter 16 will serve to retain the pin in position.

The upper and lower faces of the ends of the spring plank are provided with pockets 17 and 18 each adapted to seat the elliptic spring 19 which carries the bolster 20 upon which the vehicle body 21 is supported through the truck and body center plate 80 structure indicated at 22.

The bottom of pockets 17 and 18 is located at different distances from the axis A of the pins 13 and by removing pins 13 and turning the spring plank up side down, the springs 19 and bolster 20 will be supported at a higher level than that shown in Figures 2 and 3. Conversely, the spring plank may again be reversed and the level of the springs and bolster lowered. If the springs should

become deformed below their normal height, it would be desirable to raise their seats and if, later, new springs of greater height should be substituted, it would be desirable to again 5 reverse the spring plank to provide the lower mounting.

Irrespective of which way the spring plank is turned, there is no projection below the lower ends of links 8 and the clearance between the spring plank structure and the rail 10 is substantially greater than in previous structures in which a cross bar extended below the spring plank and was connected to the hanger links.

15 In the modification illustrated in Figures 4, 5 and 6, the spring plank 23 is provided with extensions 24 similarly to the extensions provided on the spring plank 10 shown in the preferred structure but the openings 25 for receiving the links 26 are U-shaped instead of rectangular, the outer ends of the openings being unclosed. In order to provide adequate strength for this portion of the spring plank, the outer side wall 27 of each opening is connected with the inner side wall 28 by a web 29 which also merges with the single end wall 30 of the opening. The pins 31 are seated in extensions 24 similarly to the seating shown in the preferred structure and are retained in place by suitable cotters inserted through holes 32. In this form of the invention, the spring plank is not reversible and only one spring seat pocket 32 is provided at each end 35 of the spring plank. The cross bar usually provided below the spring plank is eliminated, however, and the portions of the spring plank to which the links are connected are strengthened substantially by use of the deeper vertical walls 27 and 28 and by use of the connecting web 29.

We claim:

1. In a truck of the class described, a frame, swinging links suspended from said frame, a spring plank having rectangular openings extending vertically through its end portions and receiving and surrounding the lower ends of said swinging links, and pivot pins extending through said links and the adjacent walls of said openings.

50 2. In a truck of the class described, a frame, swinging links suspended from said frame, a spring plank having openings for receiving the lower ends of said swinging links, and pivot pins extending through said links and the adjacent sides of said openings.

3. In a truck of the class described, a frame having spaced center transoms, swinging links suspended from said transoms, a bolster between said transoms, bolster springs carrying said bolster, a spring plank beneath said springs and provided with enlarged end portions extending under said transoms, and swinging links suspended from said transoms 55 at the sides of said springs with their lower

ends pivoted directly to the enlarged portions of said spring plank.

4. In a truck of the class described, a frame, a spring plank, swinging links supporting said spring plank from said frame, said spring plank having a plurality of spring seats at each end arranged to support a spring carried thereon at different levels relative to said frame.

5. In a truck of the class described, a frame, a spring plank, swinging links supporting said spring plank from said frame, said spring plank being reversible and provided with spring seat elements on both its upper and lower sides.

80 6. In a truck of the class described, a frame, swinging links suspended therefrom, a spring plank, horizontal pins pivotally mounting said spring plank on said links, said spring plank having spring seats on its upper and lower faces located at different distances from said pins and being reversible to provide for use of either set of seats.

7. A spring plank for car trucks reversible top for bottom and provided with spring seats on both its upper and lower faces.

85 8. A spring plank for car trucks reversible top for bottom and provided with spring seats on both its upper and lower faces, there being elements on said spring plank for engaging supporting members, said elements being located at different distances from the adjacent seats.

9. A car truck spring plank provided with 100 spring seats and having suspension-link receiving vertical openings at its ends and link pin bearings adjacent to said openings.

10. A car truck spring plank having suspension-link receiving openings at its ends, and having pivot pin seats at the sides of 105 said openings.

11. A car truck spring plank having laterally enlarged end portions provided with suspension-link receiving vertical openings, and there being link pin bearings adjacent to said 110 openings.

12. In a truck of the class described, a frame, swinging links suspended from said frame, and a spring plank carried by said links and reversible top for bottom to provide a different height of support for springs mounted thereon.

13. In a truck of the class described, a frame, a spring plank, and a swinging link suspended from said frame with its lower end 120 projecting through said spring plank and supporting the same.

14. A car truck spring plank provided with spring seats at its ends with portions projecting laterally beyond said seats, there being suspension-link receiving openings disposed vertically in said portions at the sides of said seats.

15. In a railway car truck, journals, boxes thereon, a truck mounted on said boxes, links 130

pivottally suspended from opposite sides of said frame, a member extending across said frame and having vertical openings receiving the downwardly extending lower ends of 5 said links, elements pivoting said link ends to said member, said member being swingingly suspended by said links, and a bolster carried by said member.

In testimony whereof we hereunto affix our 10 signatures this 20th day of May, 1980.
